UNITED STATES PATENT OFFICE.

ROBERT EDWARD JACKSON, OF PRINCETON, WEST VIRGINIA.

HAND-BRAKE.

1,396,119.

Specification of Letters Patent.

Patented Nov. 8, 1921.

Application filed May 3, 1920. Serial No. 378,590.

To all whom it may concern:

Be it known that I, ROBERT E. JACKSON, a citizen of the United States, residing at Princeton, in the county of Mercer and State 5 of West Virginia, have invented certain new and useful Improvements in Hand-Brakes, of which the following is a specification.

This invention relates to improvements in hand brakes, and more particularly to operating mechanism for hand brakes of railway cars and the like.

An important object of the invention is to provide an operating mechanism for hand brakes, whereby the force delivered is much 15 greater than in the ordinary form of hand brakes.

In the accomplishment of my invention, I employ a multiple thread worm, rotating in fixed bearings, and a shiftable block or 20 rack engaging the worm.

I am aware that the use of a shiftable block and worm is old, but in the devices of this type with which I am familiar, the loss of energy due to friction is greatly magnified and the parts of the device accordingly quickly become worn. The wear and tear on these devices is increased by the fact that the worm screw is provided with but 25 a single thread and must accordingly, in order to give sufficient engagement to the block, have a very low pitch in order that a sufficient number of threads will engage the block to prevent the thread being stripped by the pole engaged thereon. This further 30 renders the braking action delivered very slow. With my device, any desired braking ratio and velocity of application may be obtained through the pitch or number of threads of the worm.

40 The above objections I have overcome by the combination and arrangement of parts shown in the accompanying drawings, wherein like numerals designate like parts throughout, and wherein:

45 Figure 1 is a sectional view taken through apparatus embodying my invention,

Fig. 2 is a side elevation thereof, the brake rod pull block being omitted, and,

50 Fig. 3 is a section taken on line 3—3 of Fig. 1.

Referring now more particularly to the drawings, the numeral 10 indicates a casing

provided with apertured ears 11, which are adapted to receive, through the apertures thereof, securing means 12, by means of 55 which the casing 10 is secured to the wall 13 of the car.

The casing 10 comprises sections 14 and 15, secured together by any suitable securing means 15'. A multiple threaded worm 60 16, is mounted in apertures 17, formed in the upper and lower ends of the casing section 14. The upper end 18 of the worm extends without the casing and is provided with the usual operating hand wheel 19. 65

The casing section 15 is provided with a longitudinal slot paralleling the axes of the worm and having a substantially wide side 20, which forms the side of the slot farthest removed from the worm 16. From the ends 70 of the side 20 of the recess, the walls of the recess converge toward the worm 16, being provided at their inner ends with parallel portions 22.

A rack block 23 is slidably mounted in the 75 recess and conforms in shape thereto, having portions extending between the parallel portions 22, provided with teeth 24, which engage the threads of the worm 16. The rear face of the block 23 or portion farthest removed from the worm 16 is spaced from the wall 20 of the recess. This rear face is provided with a longitudinal groove 26, which is centrally located and divides the rear face 80 into spaced arms. These arms are provided 85 with alined grooves 27, which are adapted to receive trunnions 28, secured to, or formed integrally with, rollers 29. These rollers bear against the rear wall 20 of the recess and hold the block 23 so that its teeth 24 90 are in firm engagement with the threads of the worm 16. It will be seen that the block cannot move toward the worm far enough to bind thereagainst.

Secured to the block 23 is a connecting 95 member 30 which extends through suitable apertures formed in the casing and is connected with a brake rod pull block 31.

The brake rod pull block 31 comprises an end member 32 provided with an annularly 100 arranged depending flange 33, which is internally screw-threaded to receive a sleeve 34. The lower end of the sleeve 34 is screw-threaded to receive the flange 35 of a mem-

ber 36, which is slidably mounted upon the pull rod 37 of the brake. The sleeve 34 is held against accidental displacement with respect to the flanges 33 and 35, by screws 5 35' or the like.

Within the sleeve 34, the pull rod 37 is provided with a flange 38 and a spring 39 of the compression type extending intermediate the flange 38 and the member 36.

10 In the operation of my device, when the hand wheel 19 is rotated in the direction of the arrow in Fig. 1, the threads of the worm 16 passing through the rack of the block 23, tend to cause the teeth thereof to move 15 back out of engagement with the threads of the worm. This thrust is taken care of by the anti-friction rollers 29. It will be observed that these rollers are of considerable size and keep the block 23 well spaced from 20 the rear wall of the recess. They will, however, allow sufficient shifting of the block 23 to prevent binding thereof upon the side walls 21 of the recess.

The construction shown in the pull block 25 31 is calculated to overcome any sudden stress which might otherwise be placed by the pull rod 37 on the block 23. Very often, in tightening brakes, particularly where the car upon which the brakes are being tightened is moving, the brake, in taking hold, 30 grabs very suddenly and applies a sudden and forcible jerk to the pull rod thereof. It will, of course, be obvious that with the present construction, this jerk will be cushioned by the spring 39.

35 It is to be understood that the form of my invention herewith shown and described is to be taken as a preferred example of the same, and that various changes in the shape, 40 size, and arrangement of parts may be resorted to without departing from the spirit

of the invention or the scope of the subjoined claims.

Having thus described my invention, I claim:

45 1. In a device of the character described, a casing embodying flanges, a multiple threaded worm mounted therein, said flanges being parallel to the axis of the worm, a rack block slidably mounted in said flanges and having teeth engaging said worm on one side, and an anti-friction element carried by said block on the opposite side thereof and contacting said casing.

2. In a device of the character described, 55 a casing, a worm rotatably mounted within said casing, said casing being provided with a longitudinal recess parallel to the axis of said worm, said recess being tapered transversely and having the widest portion thereof disposed at a point remote from said worm, and a block slidably mounted in said recess and having teeth on one side engaging said worm.

3. In a device of the type described, a cas- 65 ing, a worm rotatably mounted within said casing, said casing being provided with a longitudinal recess paralleling the axis of said worm, said recess being transversely tapered and having the widest portion thereof disposed at a point remote from said worm, a block slidably mounted in said recess and having upon one side, teeth engag- 70 ing said worm, and antifriction elements disposed between the opposite face of said block and the wall of the recess.

In testimony whereof I affix my signature in presence of two witnesses.

ROBERT EDWARD JACKSON.

Witnesses:

JOSEPH H. EVANS,
J. E. SULLIVAN.
